ATTYS.

UNITED STATES PATENT OFFICE.

EDWARD BARRETT, OF FALL RIVER, MASSACHUSETTS.

BOILER-FURNACE.

SPECIFICATION forming part of Letters Patent No. 404,378, dated June 4, 1889.

Application filed March 11, 1889. Serial No. 302,818. (No model.)

To all whom it may concern:

Be it known that I, EDWARD BARRETT, of Fall River, in the county of Bristol, State of Massachusetts, have invented a certain new and useful Improvement in Boiler-Furnaces, of which the following is a description sufficiently full, clear, and exact to enable any person skilled in the art or science to which said invention appertains to make and use the same, reference being had to the accompanying drawing, forming part of this specification, in which—

Figure 1 is a front elevation of a boiler-furnace provided with my improvement; Fig. 2, a top plan view, the body of the furnace being broken away; and Figs. 3, 4, and 5, enlarged sectional views illustrating certain details of construction.

Like letters and figures of reference indicate corresponding parts in the different figures of the drawings.

My invention relates to means whereby the doors of boiler-furnaces may be simultaneously opened when it becomes necessary to damp the fires; and it consists in certain novel features, as hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the furnace-front, and B C the doors. The doors are fastened by latches *b* in the usual manner, the doors B C of each set opening outward in opposite directions. Two parallel horizontally-arranged rods *d f* are disposed above the doors, said rods being supported by and fitted to slide longitudinally between rolls *g*, (see Fig. 5.) journaled in brackets *h*, which are secured at suitable intervals to the furnace-front. The rods *d f* are connected at one end by a chain *i*, which passes over a pulley *k*, journaled on the furnace-front. To the outer end of each latch *b* on the doors B is secured a chain *m*, the opposite ends of said chains being secured to the rod *d* at points at the rear of the vertical line of the door-hinges. Similarly-disposed chains *p* connect

the latches of the doors C with the rod *f* at points in the vertical line of the door-hinges, sufficient length of chain *m p* being thus supplied to allow a single door to be opened in the usual manner without moving said rods *d f*. Two vertically-arranged hand-levers *r t* are pivoted by their lower ends to the furnace-front at the side opposite the pulley *k*, the upper ends of said levers working in a guide-bracket *D*. The lever *r* is pivoted at *v* to the end of the rod *d*, and the lever *t* at *w* to the corresponding end of the rod *f*. The rods *d f* as disposed in the brackets *h* are outside the plane of the doors B C, as shown in Fig. 2.

In the use of my improvement to open the doors of the furnace the lever *r* is drawn outward into the position of lever *t* in Fig. 1. This causes the rod *d* to move from right to left and the rod *f* from left to right, as viewed in Fig. 1. The chains *m p*, secured to said rods, unlatch the doors as the rods are thus moved and swing them open in opposite directions in a manner that will be readily understood without a more explicit description. In moving the rods to open the door as described the lever *t* is moved into the position of lever *r* in Fig. 1, and to close the doors again said lever *t* is again forced outward, causing the rods to move back into their original position.

It will be seen that by the use of my device the furnace-doors can be quickly and easily opened when it becomes necessary from any cause to suddenly damp the fires and stop steam from generating. It will be understood that one rod only, as *d*, is employed when the doors B C open in the same direction.

Having thus explained my invention, what I claim is—

1. A device for opening furnace-doors, consisting of a rod arranged to slide on the furnace-front and connected with said doors by cords or chains, substantially as described.

2. In a device of the character described, the combination of a rod fitted to slide on the furnace-front in the direction the furnace-door swings, with a chain connecting the rod with the door-latch, and a lever for actuating said rod, substantially as described.

3. In a device of the character described, the combination of a furnace, a rod fitted to slide in guide-rolls on the front thereof, a chain connecting the door-latch with said rod at a point opposite the center thereof, and a lever pivoted to said rod and the furnace-front, substantially as and for the purpose set forth.

4. In a device of the character described, the combination of a furnace provided with doors opening in opposite directions, two rods fitted to slide in the furnace-front and having their corresponding ends connected by a chain passing over a fixed pulley, chains connecting the latches of doors opening in like directions with one of said rods, and an actuating-lever for each rod, whereby the doors may be opened or closed as said rods are moved, substantially as described.

5. The furnace A, provided with doors B, 20 having latches b, in combination with the rod d, fitted to slide between rolls g on the furnace-front, the chains m, connecting said latches and rod, and the lever r, for actuating said rod, substantially as described. 25

6. The furnace A, provided with doors B C, having latches b, in combination with the rods d f, fitted to slide between rolls g on the furnace-front, the chains m p, connecting said latches and rods, the chain i and pulley k, 30 and the levers r t, all being arranged to operate substantially as described.

EDWARD BARRETT.
